UNITED STATES PATENT OFFICE.

JACOB A. JACOBS, OF ST. LOUIS, MISSOURI.

DESIGN FOR A FINGER-RING.

51,067.

Specification for Design.

Patented July 24, 1917.

Application filed May 21, 1917. Serial No. 170,069. Term of patent 3½ years.

To all whom it may concern:

Be it known that I, JACOB A. JACOBS, a citizen of the United States, residing at St. Louis, in the county of Saint Louis city and State of Missouri, have invented a new, original, and ornamental Design for Finger-Rings, of which the following is a specification, reference being had to the accompanying drawing, forming a part thereof.

Figure 1 is a front elevation of a finger ring showing my new design;

Fig. 2 is a bottom plan view of the same; Fig. 3 is a side elevation of Fig. 2; and Fig. 4 is a perspective view of the same.

I claim:

The ornamental design for a finger ring, as shown.

JACOB A. JACOBS.

Witnesses:

J. G. W. SCHOENTHALER,
BRAINARD RYAN.
